and Theodore J. Sweger, 9024 Jones Ave., Naperville,
Ill.

Filed Nov. 26, 1963, Ser. No. 325,887
20 Claims. (Cl. 308—40)

This application is a continuation-in-part of application Serial No. 292,224, filed July 2, 1963, now abandoned.

This invention relates, generally, to railway car journal boxes and it has particular relation to axle journal guides therefor. It constitutes an improvement over the construction shown in Sweger Patent No. 3,104,919, issued September 24, 1963.

Among the objects of this invention are: To distribute more widely the area of the journal guides available for engagement by the axle journal than is available in the construction disclosed in the patent above referred to; to provide for mounting a pair of journal guides on opposite sides of each stop column by a one piece spring wire frame; to construct the journal guide assembly in such manner that it can be applied to the journal box without requiring that the car side frame be dismantled and the axle journal removed from the journal box; to fabricate the one piece spring wire frame from front and rear spring sections joined together between the journal guides of each pair; to arrange the juxtaposed ends of the front and rear sections so that they extend upwardly between the journal guides of each pair and to secure them together with a retainer clip; to construct the retainer clip to conform to the inverted T-shaped configuration of the underlying end portions of the front and rear sections of the spring wire frame; to position the upper ends of the retainer clips in juxtaposition to the downwardly facing concave surfaces of the brass stop columns, thereby holding the journal guides against movement around the axle journal; to position the intermediate portions of the front and rear sections of the spring wire frame in generally parallel relation and to curve them to conform to the upwardly curved surface of the bottom wall of the journal box; to construct each journal guide in two parts, one of non-ferrous bearing metal and the other of ferrous metal; to provide a groove around the ferrous metal part for receiving the one piece spring wire frame; to employ for the ferrous metal part a support ferrule for receiving an extension from the non-ferrous metal part which is deformed to hold the two parts in inseparable relation; to mount each pair of journal guides on a tie plate that is carried intermediate its ends on the spring wire frame; to interlock each journal guide with the tie plate; to mount the two parts of each journal guide on opposite sides of the tie plate and to secure them together through the tie plate; and to construct the spring wire frame of front and rear sections with the juxtaposed ends clamped to the tie plate.

In the drawings:

FIG. 1 is a vertical sectional view taken generally along the line 1—1 of FIG. 3.

FIG. 2 is a vertical sectional view taken generally along the line 2—2 of FIG. 1, the axle being shown by broken line outline in order to depict more clearly the details of construction of the one piece spring wire frame which supports the journal guides.

FIG. 3 is a horizontal sectional view taken generally along the line 3—3 of FIG. 2.

FIG. 4 is a view, similar to FIG. 2, but showing the journal box in elevated position with the journal brass or bearing and the wedge removed for the purpose of facilitating the application of the spring wire frame carrying

2

the journal guides constructed in accordance with this invention.

FIG. 5 is a sectional view taken generally along the line 5—5 of FIG. 4.

FIG. 6 is a vertical sectional view taken generally along the line 6—6 of FIG. 3.

FIG. 7 is a vertical sectional view, similar to FIG. 1, taken along the line 7—7 of FIG. 9, and showing a modified construction for mounting the journal guides on the one piece spring wire frame.

FIG. 8 is a vertical sectional view taken generally along the line 8—8 of FIG. 7, the car axle being shown by broken lines in order to show the details of construction of the journal guides by full lines.

FIG. 9 is a horizontal sectional view taken generally along the line 9—9 of FIG. 7, one of the journal guides being shown in section.

FIG. 10 is a plan view of the tie plate that is employed for mounting the journal guides as shown in FIGS. 7, 8 and 9.

FIG. 11 is a view, at an enlarged scale, taken generally along the line 11—11 of FIG. 9 to show how the journal guides can be shimmed when they are installed in an oversize journal box.

FIG. 12 is an elevational view looking in the direction of the arrows along line 11—11.

Referring now particularly to FIGS. 1, 2 and 3 of the drawings, it will be observed that the reference character 10 designates, generally, a railway car axle which in FIGS. 2 and 3 is shown by a broken line outline in order to illustrate more clearly the details of construction of the invention. The railway car axle 10 includes an axle journal 11 provided with an end collar 12 and it is arranged to rotate about an axis of rotation or its longitudinal axis which is indicated at 13. The axle journal 11 is mounted within a railway car journal box, indicated generally at 14, which is of conventional construction. The railway car journal box 14 includes a horizontal top wall 15 from which vertical side walls 16—16 depend. They are interconnected at their lower ends by a bottom wall 17 which has a concave inner surface 18. This may be a cylindrical surface. The concave inner surface 18 of the bottom wall 17 terminates at its forward end, FIG. 2, in a concave inner surface 19 on the inner side of an end wall 20 which is located below a lid opening 21 (the lid not being shown). The rear end of the concave inner surface 18 of the bottom wall 17 terminates in a vertical wall 22 of a dust guard well 23 which is completed by a vertical wall 24. Formed integrally with the depending vertical side walls 16—16 are brass stop columns 25—25 having concave surfaces 26—26 at their lower ends. The brass stop columns 25—25 serve to guide ends 27—27 of a journal brass or bearing 28 which is arranged to engage the surface of the axle journal 11. The journal brass or bearing 28 is surmounted by a wedge 29 which, together with the journal brass or bearing 28, is held in position by a wedge stop 30 that depends from the under surface of the top wall 15 adjacent the lid opening 21.

In order to limit the lateral movement of the axle journal 11 in the journal box 14, journal guides, shown generally at 33, are provided. They are located along diametrically opposite sides of the axle journal 11 at the elevation of the axis 13 and are four in number. The journal guides 33 of each pair are positioned, as shown in FIGS. 2 and 3, on opposite sides of the respective brass stop column 25 and thus provide a relatively large area for engaging the diametrically opposite sides of the axle journal 11.

In FIG. 5 there is shown in detail the construction of one of the journal guides 33. Here it will be observed that each journal guide 33 includes a bearing section 34 that may be formed of forged bronze bearing alloy. It

has a front or bearing face 35 that is juxtaposed to the bearing surface of the axle journal 11. On the opposite side the bearing section 34 has an integral extension 36 which is telescoped within a support ferrule 37 that may be formed of pearlitic malleable iron. The extension 36 is deformed at 38 for the purpose of providing a unitary construction. The inner surface 39 of the support ferrule 37 is arranged, as shown in FIG. 3, to bear against the inner surface of the respective side wall 16 of the journal box 14.

An annular groove 40 is formed in the support ferrule 37 for receiving a turn 41 of a one piece spring wire frame that is indicated, generally, at 42. It will be understood that the several turns 41, one for each of the journal guides 33, are formed in the one piece spring wire frame 42. Then a support ferrule 37 is inserted in each of the turns 41 and thereafter a bearing section 34 is inserted and the extension 36 deformed to provide the integral construction shown in FIG. 5.

Preferably the one piece spring wire frame 42 initially is formed of a front section, indicated generally at 43, and a rear section, indicated generally at 44. These sections 43 and 44 are constructed of spring steel wire and, as seen in FIG. 2, they are generally inclined and parallel to each other. Their central portions 45 and 46 are curved, as indicated in FIGS. 1 and 3, in order to conform to the upwardly curved inner surface 18 of the bottom wall 17 of the journal box 14. The rear section 44 has shoulder portions 47—47, FIG. 3, that are arranged to bear against the adjacent surface of the vertical wall 22 and thereby limit the inward movement of the spring wire frame 42 assembled with the journal guides 33.

As seen more clearly in FIGS. 2 and 3 of the drawings the front section 43 has lateral portions 51—51 in endwise relation to lateral portions 52—52 of the rear section 44. The ends 53—53 and 54—54 extend upwardly in juxtaposed relation intermediate the pairs of journal guides and are held together by retainer clips 55—55 which, as shown in FIG. 6, are deformed to provide an inverted T-shaped configuration overlying the lateral portions 51—51 and 52—52 of the front and rear sections 43 and 44 with the stem overlying the vertically extending ends 53—53 and 54—54. The retainer clip 55 is generally U-shaped in cross section and is formed of mild steel. The outer upwardly extending portions are deformed into juxtaposed relation and are secured together in a suitable manner such as by spot welding as indicated at 56.

It will be understood that the one piece spring wire frame 42 is assembled exteriorly of the railway car journal box 14. The ends are secured together by the retainer clips 55 and the journal guides 33 are mounted within the turns or loops 41 in the manner described.

In order to apply the assembled one piece spring wire frame 42 with the journal guides 33, the journal box 14 is elevated by jacking until the hub portion 57 of the axle 10 is engaged by the walls 22 and 24. This permits removal of the journal brass or bearing 28 and the wedge 29 since the latter is now located below the wedge stop 30. Next the rear section 44 of the one piece spring wire frame 42 with the journal guides 33 assembled therein is inserted, as shown in FIG. 4 by full lines, in the lid opening 21. It is moved inwardly through the journal box 14 to the position shown by broken lines where one corner of the retainer clip 55 engages the outer side of the brass stop column 25. Just before this takes place the front section 43, which remains outside of the lid opening 21, is sprung upwardly and inwardly so that, on continued inward movement of the assembly, it slides downwardly over the concave inner surface 19 of the end wall 20 and assumes the position indicated by broken lines in FIG. 4. The assembly then can be moved to the operative position shown in FIG. 2 where the journal guides 33 are held against the inner surfaces

of the vertical side walls 16 with the journal guides 33 being located on opposite sides of the brass stop columns 25. Then the journal brass or bearing 28 and wedge 29 are replaced and finally the journal box 14 is lowered to operative position as shown in FIG. 2. The upper ends of the retainer clips 55 engage the concave surfaces 26—26 of the brass stop columns and thereby prevent rotation of the journal guides 33 and spring wire frame 42 about the axle journal 11.

The one piece spring wire frame 42, assembled with the journal guides 33, can be removed from the journal box 14 by a reversal of the foregoing steps. It will be seen that it is unnecessary to disassemble the car truck side frame including the journal box 14 or to remove the axle 10 from the journal box 14. This reduces materially the expense incident to the application of the journal guides 33 and their removal.

Referring now particularly to FIGS. 7, 8 and 9, it will be observed that the railway car journal box 14, previously described and having the railway car axle 10 mounted therein, is provided with journal guides, each being indicated, generally, at 57, which are of a somewhat different construction than the journal guides 13 previously described. Each journal guide 57 includes a bearing section 58 that may be formed of forged bronze bearing alloy and is provided with a front or bearing surface 59 that is positioned adjacent the surface of the axle journal 11. The bearing section 58 has an integral extension 60 that projects into a support ferrule 61 that may be formed of pearlite malleable iron. The extension 60 is deformed at 62 for the purpose of securing the bearing section 58 to the support ferrule 61. The support ferrule 61 has a rear surface 63 that is arranged to engage the inner surfaces of the depending vertical side walls 16—16 of the railway car journal box 14.

In order to mount the journal guides 57 a tie plate 64, shown in detail in FIG. 10, is employed. The tie plate 64 may be formed of hot rolled steel and it is provided with rectangular openings 65—65 near its ends for receiving a generally rectangular flange 66 that forms an integral part of the support ferrule 61. In addition the support ferrule 61 is provided with a centering lug 67 that extends into a slot 68 formed on the inner side of each of the rectangular openings 65. It will be understood that the tie plate 64 is assembled with two journal guides 57, one at each end. The support ferrules 61 are positioned on one side of the tie plate 64 with the rectangular flange 66 and centering lug 67 extending into the rectangular opening 66 and slot 68. Then the bearing sections 58 are applied to the inner side of each tie plate 64 with the extension 60 projecting through the rectangular opening 65 and into the respective support ferrule 61. Thereafter the extension 60 is deformed, as indicated at 62, to provide a unitary construction. The arrangement is such that the journal guides 57, when applied to the journal box 14, are located on opposite sides of the respective brass stop column 25.

In order to hold the journal guides 57 assembled on the tie plate 64 in operative position in the journal box 14 and to permit the application thereof and removal without removing the journal box 14 from the axle journal 11, a one piece spring wire frame, shown generally at 70 and similar to the spring wire frame 42, is provided. The spring wire frame 70 includes a front section 71 and a rear section 72. These sections include central portions 73 and 74 which are curved to conform to the curvature of the concave inner surface 18 at the bottom of the journal box 14. The rear section 72 of the one piece spring wire frame 70 includes shoulder portions 72'—72' that bear against the outer side of the vertical wall 22 and serve to limit the movement of the spring wire frame 70 into the journal box 14. From the shoulder portions 72'—72' horizontal portions 75—75 extend to a position to the left of the inner journal guide 57 as seen in FIG. 8. Upstanding portions 77—77 and 78—78 extend from the

front section 71 and from the horizontal portions 75—75 along the inner surfaces of the walls 16—16 of the journal box 14. At the upper ends of the upstanding portions 77 and 78 there are forwardly extending portions 77'—77' and 78'—78', FIG. 9, that are directed toward the central portion of the journal box 14. From the inner ends of these forwardly extending portions 77' and 78' there are lateral portions 79—79 and 80—80 which overlie the outer side of each of the tie plates 64. These lateral portions 79 and 80 extend toward each other as best seen in FIG. 8 and terminate in upstanding end portions 81—81 and 82—82 which also overlie the outer sides of the tie plates 64. The lateral portions 79 and 80 with the upstanding end portions 81 and 82 form an inverted T-shaped configuration with the extreme ends 83—83 and 84—84 extending toward the concave surfaces 26—26 and engaging the same as shown in FIG. 7. This arrangement with the end portions 83 and 84 juxtaposed to the concave surfaces 26—26 serve to prevent movement of the spring wire frame 70 and the journal guides 57 carried thereby in either direction around the axle journal 11.

In order to secure the juxtaposed lateral portions 79 and 80 and upstanding end portions 81 and 82 of the sections 71 and 72 of the spring wire frame 70 to the outer sides of the tie plates 64 a wire retainer cover plate or clip 85, preferably formed of mild steel, is employed. Each cover plate or clip 85 is formed with an inverted T-shaped groove 86, FIG. 8, in order to permit the juxtaposed faces of the tie plates 64 and cover plates or clips 85 to come into surface contact engagement. They are held together by projection welding which is facilitated by the provision of projections 87, FIG. 10, preferably four in number. In order to accurately locate the cover plate or clip 85 a locator lug 88, FIG. 10, is deformed therefrom and is arranged to enter an aperture (not shown) in the adjacent cover plate or clip 85.

After the journal guides 57 have been assembled with the tie plate 64 in the manner described, the front and rear sections 71 and 72 of the spring wire frame 70 are positioned in the relationship shown in FIGS. 7, 8 and 9 in a suitable jig and the cover plates or clips 85 are properly positioned and clamped in place. Then, by projection welding, the cover plates 85 are welded to the tie plates 64 in order to provide a unitary construction.

The manner in which the one piece spring wire frame 70 assembled with the journal guides 57 is applied to and removed from the journal box 14 is essentially the same as described hereinbefore for the one piece spring wire frame 42 having the journal guides 33 assembled thereon. An important advantage of the use of the tie plate 64 is that it securely holds the journal guides 57 in position inside the journal box 14. Also it facilitates the action of the spring wire frame 70 in urging the journal guides 57 into good contact engagement with the side walls 16—16.

There are some journal boxes 14 that are oversize a slight amount. In order to employ the same assembly of the spring wire frame 70 and journal guides 57 provision is made as shown in FIGS. 11 and 12 for positioning a shim 91 behind each support ferrule 61 and between its rear surface 63 and the adjacent surface of the side wall 16. The shim 91 is formed of suitable metal and includes ears 92—92 that can be turned over a laterally extending flange 93 at the outer side and outer end of the support ferrule 61. A lug 94, on the opposite side of the shim 91, overlies the adjacent surface of the support ferrule 61 and serves to hold the shim in position.

What is claimed as new is:

1. In combination:

- (a) a railway car journal box having a bottom wall interconnecting its side walls from which stop columns extend inwardly and an axle journal spaced from said side walls,
- (b) a pair of journal guides on opposite sides of each stop column and interposed between each side wall

and the diametrically opposite sides of said axle journal,

- (c) each journal guide having a body portion with a front face juxtaposed to said axle journal and a rear face bearing against the respective side wall, and
- (d) a one piece spring wire frame and means carried thereby for supporting each journal guide intermediate its front and rear faces, restraining said journal guides against movement in a vertical plane, biasing them toward the respective side wall of said journal box and having its end portions overlying the respective side walls of said journal box.

2. The invention, as set forth in claim 1, wherein the one piece spring wire frame comprises front and rear sections joined together intermediate the journal guides of each pair.

3. The invention, as set forth in claim 2, wherein:

- (a) the juxtaposed ends of the front and rear sections extend upwardly between the journal guides of each pair, and
- (b) a retainer clip overlies each pair of juxtaposed ends and laterally extending adjacent portions of the front and rear sections of the spring wire frame.

4. The invention, as set forth in claim 3, wherein the upper ends of the retainer clips are juxtaposed to undersides of the stop columns and thereby movement of the journal guides and spring wire frame is prevented.

5. The invention, as set forth in claim 3, wherein each retainer clip is of generally U-shape and conforms to the shapes of the upwardly extending ends and laterally adjacent portions of the front and rear sections of the spring wire frame.

6. The invention, as set forth in claim 2, wherein:

- (a) the inner surface of the bottom wall of the journal box is curved upwardly, and
- (b) the intermediate portions of the front and rear sections are generally parallel to each other and extend uninterruptedly along said inner surface of said bottom wall.

7. The invention, as set forth in claim 1, wherein the one piece spring wire frame is wrapped around each journal guide intermediate its front and rear surface.

8. The invention, as set forth in claim 1, wherein each journal guide comprises:

- (a) a bearing section carrying the front face on one side and having on the opposite side a deformable extension, and
- (b) a support ferrule carrying the rear face and telescoped over said extension which is deformed to provide a unitary construction.

9. The invention, as set forth in claim 8, wherein the ferrule has an annular groove for receiving the one piece spring wire frame therein.

10. In combination:

- (a) a railway car journal box having a bottom wall interconnecting its side walls from which stop columns extend inwardly and an axle journal spaced from said side walls,
- (b) a pair of journal guides on opposite sides of each stop column and interposed between each side wall and the diametrically opposite sides of said axle journal,
- (c) each journal guide having a body portion with a front face juxtaposed to said axle journal and a rear face bearing against the respective side wall,
- (d) a tie plate supporting at its ends each pair of journal guides, and
- (e) a one piece spring wire frame supporting each tie plate intermediate its ends, restraining it and the journal guides carried thereby against movement in a vertical plane, biasing the journal guides toward the respective side wall of said journal box and having its ends overlying the respective side walls of said journal box.

11. The invention, as set forth in claim 10, wherein each journal guide comprises:

- (a) a bearing section carrying the front face on one side and having on the opposite side a deformable extension, and
- (b) a support ferrule carrying the rear face and telescoped over said extension which is deformed to provide a unitary construction.

12. The invention, as set forth in claim 11, wherein:

- (a) the tie plate has an opening near each end,
- (b) the support ferrule is positioned on the outer side of the tie plate and has a flange extending into the opening, and
- (c) the bearing section is positioned on the inner side of the tie plate with the extension extending through the opening therein.

13. The invention, as set forth in claim 12, wherein:

- (a) the opening in the tie plate is rectangular,
- (b) the flange on the support ferrule fits snugly with said opening, and
- (c) a centering lug extends from the support ferrule into a slot at one side of said opening in said tie plate.

14. The invention, as set forth in claim 10, wherein:

- (a) the one piece spring wire frame comprises front and rear sections with juxtaposed upstanding end portions from laterally adjacent portions of said front and rear sections in overlying relation to the outer side of each tie plate, and
- (b) a retainer clip grooved to conform to said upstanding end portions and said laterally adjacent portions and overlying the same and the outer side of each tie plate and secured thereto.

15. The invention, as set forth in claim 10, wherein:

- (a) each journal guide has a flange adjacent the respective side wall of the journal box,
- (b) a shim is interposed between each journal guide and its side wall, and
- (c) means on the shim engage the flange and hold said shim in place.

16. In combination:

- (a) a railway car journal box having a bottom wall interconnecting its side walls from which brass stop columns extend toward each other, a dust guard wall, and an axle journal spaced from said side walls,
- (b) journal guide means on diametrically opposite sides of said axle journal between it and the respective side wall, and
- (c) a unitary spring wire frame supporting said journal guide means in operative position in said journal box including:
  - (1) front and rear sections engaging said bottom wall,
  - (2) lateral portions between the upper ends of said front and rear sections and supporting said journal guide means thereabove, and
  - (3) shoulder portions interconnecting said lateral portions and said rear section and bearing against said dust guard wall,
  - (4) the central portion of said rear section being spaced outwardly from said dust guard wall to

facilitate application of said journal guide means assembled with said unitary spring wire frame to operative position past said brass stop columns with said axle journal in said journal box.

17. The invention, as set forth in claim 16, wherein the front section of the spring wire frame in operative position in the journal box is generally parallel to the rear section.

18. The invention, as set forth in claim 16, wherein the shoulder portions bear against the dust guard wall in a horizontal plane generally parallel to and below the axis of rotation of the axle journal and adjacent thereto.

19. In combination:

- (a) a railway car journal box and an axle journal therein between the side walls thereof,
- (b) journal guide means on diametrically opposite sides of said axle journal between it and the respective side wall each including:
  - (1) a bearing section carrying an uninterrupted front face juxtaposed to said axle journal and having on the opposite side an integral deformable extension, and
  - (2) a support carrying a rear face reacting against the respective side wall and telescoped over said extension which is deformed to provide with said bearing section a unitary construction; and
  - (c) a unitary spring wire frame supporting said journal guide means in operative position in said journal box.

20. In combination:

- (a) a railway car journal box having a bottom wall interconnecting its side walls from which brass stop columns extend toward each other, a dust guard wall, and an axle journal spaced from said side walls,
- (b) journal guide means on diametrically opposite sides of said axle journal between it and the respective side wall each including:
  - (1) front and rear sections engaging said bottom wall and having upper ends juxtaposed to undersides of said brass stop columns,
  - (2) lateral portions between said upper ends supporting said journal guide means,
  - (3) shoulder portions interconnecting said lateral portions and said rear section and reacting against said dust guard wall, and
  - (4) the central portion of said rear section being spaced outwardly from said dust guard wall to facilitate application of said journal guide means assembled with said unitary spring wire frame to operative position past said brass stop columns with said axle journal in said journal box.
